(57) **CLAIM**

The ornamental design for an umbrella base, as shown and described.

DESCRIPTION

FIG. 1 is a perspective view of an umbrella base, shown with environment for ease of disclosure;

FIG. 2 is another perspective view of the umbrella base;

FIG. 3 is an enlarged view of a single hook element of the umbrella base, shown separately for ease of disclosure;

FIG. 4 is an enlarged view of the hook elements secured to the umbrella post of the umbrella base, shown separately for ease of disclosure;

FIG. 5 is a front view of the umbrella base;

FIG. 6 is a rear view thereof;

FIG. 7 is a left side view thereof;

FIG. 8 is a right side view thereof;

FIG. 9 is a top view thereof; and,

FIG. 10 is a bottom view thereof.

The broken lines depict portions of the article and environment that form no part of the claimed design.

1 Claim, 8 Drawing Sheets
